(57) **CLAIM**

The ornamental design for a column for machining center, as shown and described.

DESCRIPTION

FIG. 1 is a front elevation of a column for machining center in place in a machining center and showing the design;

FIG. 2 is a top plan view of the column for machining center of FIG. 1 in place in a machining center;

FIG. 3 is a left side elevation of the column for machining center of FIG. 1 in place in a machining center;

FIG. 4 is a right side elevation of the column for machining center of FIG. 1 in place in a machining center;

FIG. 5 is a rear elevation of the column for machining center of FIG. 1 in place in a machining center;

FIG. 6 is a perspective view taken from the front, top and right side of the column for machining center of FIG. 1 in place in a machining center;

FIG. 7 is a front elevation of the column for machining center of FIG. 1 showing the design;

FIG. 8 is a top plan view of the column for machining center of FIG. 7;

FIG. 9 is a left side elevation of the column for machining center of FIG. 7;

FIG. 10 is a right side elevation of the column for machining center of FIG. 7;

FIG. 11 is a rear elevation of the column for machining center of FIG. 7;

FIG. 12 is a bottom plan view of the column for machining center of FIG. 7;

FIG. 13 is a sectional view taken along the line 13—13 in FIG. 7; and,

FIG. 14 is a perspective view taken from the rear, top and right side of the column for machining center of FIG. 7.

The broken line showing of the machining center in FIGS. 1-6 is included for the purpose of illustrating the environment of the column for machining center and forms no part of the claimed design.
